[57] CLAIM

The ornamental design for a display package for drill bit, as shown and described.

DESCRIPTION

FIG. 1 is a front perspective view of a display package for drill bit showing my new design;

FIG. 2 is a rear perspective view thereof;

FIG. 3 is a left side elevation thereof; the right side elevation being a mirror image thereof;

FIG. 4 is a bottom plan view thereof;

FIG. 5 is a top plan view thereof; and

FIG. 6 is a perspective view of a modified form of FIG. 1 thereof.

FIG. 3

FIG. 4

FIG. 5
